US00D932094S

(12) **United States Design Patent** (10) **Patent No.:** **US D932,094 S**
(45) **Date of Patent:** **** Sep. 28, 2021**

(54) **VAPORIZER CARTRIDGE**

(71) Applicant: **CANOPY GROWTH CORPORATION**, Smiths Falls (CA)

(72) Inventors: **Kyle Laidlaw**, Brooklyn, NY (US); **Johan Liden**, Brooklyn, NY (US); **Bach Nguyen**, San Francisco, CA (US); **Danvu Nguyen**, San Francisco, CA (US); **Brett Tom**, Richmond, CA (US)

(73) Assignee: **CANOPY GROWTH CORPORATION**, Smiths Falls (CA)

(**) Term: **15 Years**

(21) Appl. No.: **29/717,041**

(22) Filed: **Dec. 13, 2019**

(51) LOC (13) Cl. **27-02**
(52) U.S. Cl.
USPC **D27/162**

(58) **Field of Classification Search**

(57) **CLAIM**

The ornamental design for a vaporizer cartridge, as shown and described.

DESCRIPTION

FIG. 1 is a perspective view of a vaporizer cartridge; FIG. 2 is a front elevational view of the vaporizer cartridge of FIG. 1;

FIG. 3 is a rear elevational view of the vaporizer cartridge of FIG. 1;

FIG. 4 is a right side elevational view of the vaporizer cartridge of FIG. 1;

FIG. 5 is a left side elevational view of the vaporizer cartridge of FIG. 1;

FIG. 6 is a top plan view of the vaporizer cartridge of FIG. 1; and,

FIG. 7 is a bottom plan view of the vaporizer cartridge of FIG. 1.

The broken lines in the drawings illustrate portions of the vaporizer cartridge that form no part of the claimed design.
